DESIGN FOR A COMBINED DISPLAY AND CONTAINER CABINET FOR MANICURING IMPLEMENT OR SIMILAR ARTICLE

Carl W. Gardiner, Short Hills, N. J.

Application October 7, 1936, Serial No. 65,192

Term of patent 7 years

To all whom it may concern:

Be it known that I, Carl W. Gardiner, a citizen of the United States, residing at Short Hills in the county of Essex and State of New Jersey, have invented a new, original, and ornamental Design for a Combined Display and Container Cabinet for Manicuring Implements, or Similar Article, of which the following is a specification, reference being had to the accompanying drawing, forming a part thereof.

I claim:

The ornamental design for a combined display and container cabinet for manicuring implements, or similar article, as shown.

CARL W. GARDINER.
